SPECTACLE CASE

Emanuel Nathan, Maplewood, N. J.

Application April 25, 1945, Serial No. 590,131

2 Claims. (Cl. 206—5)

1

This invention relates to improvements in spectacle cases.

It is the object of this invention to provide a spectacle case which is of simple and practical construction and which may be manufactured and assembled in a simple and rapid manner.

The spectacle case of my invention incorporates novel means for the positioning of spectacles therein and for reinforcing the spectacle case at those portions thereof which bear the latching and positioning means.

These and other advantageous objects, which will later appear, are accomplished by the simple and practical construction and combination of parts hereinafter described and more particularly shown in the drawings, illustrating embodiments of my invention, in which:

Fig. 1 is a perspective view of a spectacle case embodying my invention, shown in partially open position,

Fig. 2 is an elevational view thereof in closed position,

Fig. 3 is an enlarged vertical transverse sectional view taken on line 3—3 of Fig. 2, and

Fig. 4 is a rear elevational view of the spectacle case in open position.

As shown in the drawings, the spectacle case of my invention comprises a blank 10 of flexible material, such as natural or artificial leather or analogous material, which is cut to define a front wall 11 and a rear wall 12 united thereto as at 13, said rear wall 12 terminating in a medial flap 14. The front wall 11 and rear wall 12 are preferably partly stitched together as at 15 along the longitudinal ends thereof so as to close the lower portion of the longitudinal ends of the case. The front wall 11 has an extended tab portion 17 which is defined by shoulders 16 which also substantially define the upper ends of the stitched portions 15.

The opposite ends 19 and 20 of an elongated reinforcing strip 18 (which may be of similar material to blank 10) are secured to the front wall 11 and to the terminal flap 14 by complementary fastener elements 21 and 22, which are adapted to have interlatching engagement to close the case as shown in Figs. 2 and 3. Said complementary elements 21 and 22 may be of any desired separable fastener construction, such as the well known "glove fastener" type illustrated in the drawings. The fastener element 21 is preferably formed integral with a stud 23 which is fixed to a positioning block 24 of wood or the like, said block being preferably of triangular outline to facilitate the position-

ing of spectacles thereon and to hold the spectacles in position in the case of my invention. The front and rear walls of said block 24 are preferably inwardly tapered as at 25 so that a generally arcuate configuration may be presented at the lower medial portion of the spectacle case, viewed cross sectionally at Fig. 3.

From the foregoing description it will be apparent that the spectacle case of my invention permits the use of extremely flexible material, which is highly desirable in articles of this kind, and at the same time provides for the reinforcement thereof at desired points of strain so that a rigid positioning member may be incorporated therein and those portions of the spectacle case which are provided with the complementary fastener means may be adequately reinforced without detracting from the flexible characteristics of the case.

20 The invention defined herein shall not be deemed to be limited to the embodiment thereof which is shown in the drawing and described in the specification for illustrative purposes only, but shall be deemed to include any other embodiments thereof within the purview of the appended claims.

Having thus described my invention what I claim as new and desire to secure by Letters Patent, is:

30 1. A spectacle casing comprising a blank of flexible material, said blank comprising a front wall, and a rear wall integrally united to provide a bottom wall, the ends of the front wall and the adjacent end portions of the rear wall being secured together to form a pocket, an integral medial flap formed on the upper edge of the rear wall and adapted to provide a closure for the casing, an elongated strip of similar material secured only at its ends to the front wall and to the free end portion of the medial flap respectively, said securing means comprising, fastening means extending through the flap and strip, and complementary fastening means extending through the other end of the strip and the front wall, and a spectacle positioning block secured in the pocket by the fastening means that extends through the front wall and the adjacent end portion of the strip.

2. A spectacle casing comprising a blank of flexible material, said blank comprising a front wall and a rear wall integrally united to provide a bottom wall, the ends of the front wall and the adjacent end portions of the rear wall being secured together to form a pocket, an integral medial flap formed on the upper edge of

the rear wall and adapted to provide a closure for the casing, an elongated strip of similar material secured only at its ends to the front wall and to the free end portion of the medial flap respectively, said securing means comprising, fastening means extending through the flap and strip, and complementary fastening means extending through the other end of the strip and the front wall, and a spectacle positioning block secured in the pocket by the fastening means that extends through the front wall and the adjacent end portion of the strip, the front and rear walls of said block being downwardly ta-

pered toward the bottom thereof, the side walls of the block converging upwardly.

EMANUEL NATHAN.
